UNITED STATES PATENT OFFICE.

CHARLES CROOK, JR., OF BROOKLYN, NEW YORK, ASSIGNOR TO LUTHER S. BUSH, OF NEW YORK, N. Y.

ROTARY ENGINE.

SPECIFICATION forming part of Letters Patent No. 691,604, dated January 21, 1902.

Application filed October 16, 1900. Serial No. 33,197. (No model.)

To all whom it may concern:

Be it known that I, CHARLES CROOK, Jr., a citizen of the United States, and a resident of the city of New York, borough of Brooklyn, 5 in the county of Kings and State of New York, have invented certain new and useful Improvements in Rotary Engines, of which the following is a specification.

This invention relates to improvements in rotary engines; and the object of my invention is to provide a new and improved engine of this kind which is simple in construction, strong, durable, and effective, very economical, and the parts of which can readily be disengaged and separated for inspection, repair, or adjustment and can be reassembled and united with great facility.

In the accompanying drawings, in which like letters of reference indicate like parts in all the views, Figure 1 is a side view of my improved rotary engine, parts being omitted. Fig. 2 is a front elevation, parts being in section and others omitted, the cylinder-shells and piston being separated for inspection or repair. Fig. 3 is an elevation of the side shown in Fig. 1, but in conjunction with other parts which have been omitted in Fig. 1, parts of Fig. 3 being in section. Fig. 4 is an elevation of parts shown in Fig. 3. Fig. 5 is a vertical central longitudinal section through the engine, parts being omitted. Fig. 6 is an elevation of the other side of the engine, parts being in section and others broken away. Figs. 7 and 8 are edge views of the cylinder-shells. Figs. 9, 10, 11, and 12 are vertical longitudinal sectional views of a slightly-modified form 35 of my improved engine provided with a reversing-gear, parts being omitted in some figures.

40 The engine rests upon a hollow cast base A, in which the exhaust channel or duct A' is formed. The cylinder B, which is ring-shaped, is formed in two shells B' and B'', mounted vertically on the base A and having abutting flanges B³, through which the bolts or screws B⁴ are passed for holding the shells together. Each cylinder - shell B' B'' has side lugs C resting upon supporting- ledges A² on the base A, of which ledges there 45 is one on each side of the base. Bolts or screws C', passed through the side lugs C and

the ledges A², serve to hold the cylinder-shells in place, and as these shells by means of their lugs C rest on the plates A² the two shells B' B² can easily be moved toward or from each other after the bolts or screws B⁴ and C' have been loosened or removed, the lugs C sliding on the ledges A², and can thus be moved very easily. Each shell B' B² is provided with a steam-space B⁵, into which steam at high pressure is admitted through the pipes B⁶ for the purpose of completely jacketing the cylinder. The main shaft D is mounted in a suitable bearing on a standard D' on the base A.

The piston E, fitting in the ring-shaped cylinder B, is secured on the disk E', filling in the shells B' B² and secured on the shaft D. The piston has an outer packing-strip E² and an inner packing - ring E⁶, which are both pressed radially against the cylinder-walls by 65 springs E³. A cylindrical abutment F, having a suitable recess F' for the passage of the piston E, is mounted in the cylinder and a substantially semicylindrical transverse recess F² in the outer cylinder-walls in such a 70 manner that it can turn axially parallel with the shaft D. When in the position shown in Fig. 5, it permits the piston to pass freely; but when in the position shown in Figs. 10, 11, and 12 it closes the cylinder and acts as an 75 abutment for the live steam, as it is of such dimensions and so mounted as to come in contact with the cylinder-walls. It has two longitudinal packing-strips a and b, which are so located as to be in contact with the walls 80 of the recess F² when the abutment is in position for permitting the piston to pass, as shown in full lines in Fig. 5, and when the abutment is swung up to extend across the cylinder the packing-strip a is in contact with the inner 85 cylinder-wall and the strip b is in contact with the walls of the recess F², as shown in dotted lines in Fig. 5.

A pinion G is secured on a neck on one end of the abutment F outside of the shell and is 95 engaged by a segment-rack G', formed on the lower end of an arm G², mounted to rock on the main shaft D, and this arm is connected near its lower end by a pivoted link G³ with a lever G⁴, pivoted at G⁵ to the outside of the 100 cylinder and carrying on a stud on its side an antifriction-roller G⁵, which runs in a cam-

groove G^6 , formed on one face of a cam-disk G^7 , secured on the main shaft, which cam-groove has the offset G^8 for properly throwing the lever G^4 .

5 The steam-inlet valve H is mounted to rock in a transverse cylindrical recess H' in the shell, and from said recess the steam-inlet channel H^2 extends to the cylinder. On one end of the rock-valve H a crank-arm H^3 is fixed outside of the shell and is connected by a link H^4 with the free end of a lever H^5 , pivoted to the shell at H^6 and carrying a roller H^7 , which is pressed by a spring H^8 against a cam-disk H^9 , fixed on the main shaft D and having a cam projection H^{10} of such shape and size as may be necessary according to the length of time steam is to be admitted into the cylinder. The engine can thus readily be adjusted to cut off the steam at any desired part of the stroke. The exhaust-steam duct I , which is on that side of the abutment opposite the one at which the steam-inlet is located, leads to the exhaust-channel A in the base A . Just before steam is admitted into the cylinder the abutment F is brought by its cam into the position shown in dotted lines in Fig. 5, the piston being at the right of the steam-inlet. The entering and expanding steam which is cut off at the desired point forces the piston around in the direction of the arrow x' , the exhaust-steam of the previous stroke being forced out through the exhaust-duct I . When the piston E arrives at the abutment, the same is turned for an instant into the position shown in full lines, Fig. 5, to let the piston pass and is then immediately returned to the position shown in dotted lines in Fig. 5, and so on.

When the engine needs inspection, adjustment, or repair, the bolts or screws C' and B^4 are removed and the shell B' is moved from the section B^2 , as shown in Fig. 2, the steam-valve and its operating-gear moving with the shell B^2 .

45 The abutment and its operating-gear remain in the shell B , which remains fixed on the base.

For the purpose of removing the piston and its disk from the fixed shell the main shaft is moved lengthwise, the collars, &c., on the same having been first loosened.

50 The parts can readily be reassembled by moving the shaft back lengthwise and shifting the shell B^2 up against the shell B' and then locking the parts in place.

55 In the construction shown in Figs. 9 to 12 provision is made for reversing the engine, and for this purpose the steam is not admitted direct, as described above, but through the abutment which is provided with a substantially U-shaped or segmental steam-duct J , the ends of which can register with steam-ducts in the parts of the shells. The shells are provided with the solid portion K , having a flat face K' , on which the slide-valve L' is mounted, with a steam-chest L , having a suitable steam-inlet L^2 . The valve L' may be

shifted or adjusted by means of a screw or other suitable device. From the flat face K' an exhaust-duct M extends to the outer cylinder-wall at a point near the rocking abutment. An exhaust-duct N extends from said flat face K' to the recess F and another duct O from said flat face to the exhaust-duct P . A channel R extends from the flat face K to the recess. The valve L has the usual recess Q and a wing or lip S , having an opening T .

When the engine is to run in the direction of the arrow x^2 , Figs. 9, 10, and 11, the valve L' is so shifted as to close the channel or duct M by means of the wing or lip S on said valve and to establish communication between the steam-chest L and the channel or duct N by means of the opening T in said wing S , as shown in Figs. 9, 10, and 11. At the same time the channel or duct R only is connected by the recess Q of the valve L' with the exhaust duct or channel O .

When the parts are in the position shown in Fig. 9, no steam can enter; but as soon as the piston has passed the abutment F the latter is brought into the position shown in Fig. 10, one end of the curved duct J in said abutment being in communication with the inner end of the duct N and the other with that part of the cylinder between the piston E and abutment F . The opposite end of the cylinder is brought into communication with the exhaust-channel O by the recess Q of the valve L' , the duct R and the recess F' in the abutment permitting the exhaust-steam from the previous stroke to be forced out of the cylinder by the advancing piston, which is moved in the direction of the arrow x^2 by the steam entering the cylinder through the curved duct J in the abutment F . In case it is desired to cut off the steam—say about one-quarter of the stroke, more or less—the abutment is moved back sufficiently to interrupt the communication between the duct N and the curved duct J in the abutment, as shown in Fig. 11, but without closing the duct R by the abutment. By the time the stroke is finished the abutment is moved into the position shown in Fig. 9, the steam-supply duct N is closed by the abutment, and when the piston has passed the abutment the latter is brought into the position shown in Fig. 10 again, and so on.

The cam for operating the abutment must of course be so shaped as to turn back the abutment into the position shown in Fig. 11 at the time the steam is to be cut off.

When the direction of rotation is to be reversed, the valve L' is shifted into the position shown in Fig. 12, so that communication is established by the duct M and valve L' between one end of the cylinder B and the exhaust-duct P , the live steam entering the opposite end of the cylinder through the duct R and the recess F in the abutment as long as the abutment is in the position shown in Fig. 12.

When the solid part of the abutment is swung into the recess, it closes the steam-inlet duct R, but opens it as soon as the abutment is brought into the position shown in Fig. 12.

Having described my invention, what I claim as new, and desire to secure by Letters Patent, is—

1. In a rotary engine, the combination with a base, having ledges, of cylinder-shells having lugs projecting beyond the peripheries of the shells and resting on said ledges, said ledges being entirely outside of the outer periphery of the shells, substantially as herein shown and described.
2. In a rotary engine, the combination with a base having ledges, of cylinder-shells resting vertically on said ledges and movable laterally toward and from each other on said ledges, lugs on said shells which lugs extend beyond the periphery of the shells and rest upon said ledges, a piston between the shells, a main shaft on which the piston is secured and a standard on said base on which standard the main shaft is mounted, substantially as herein shown and described.
3. In a rotary engine, the combination with a cylinder and a rotary piston therein, of a recessed cylindrical abutment, mounted to rotate axially in the cylinder and in the outer cylinder-wall, a pinion on one end of said abutment, a segment-rack engaging said pinion and mounted to swing on the engine main shaft, a cam on the main shaft, a pivoted lever engaged by said cam and a link connecting the swinging segment-rack with said pivoted lever, substantially as herein shown and described.
4. In a rotary engine, the combination with a cylinder and a rotary piston therein, of a main shaft carrying the piston, a recessed cylindrical abutment mounted parallel with the main shaft in the cylinder and a recess in the outer wall of the cylinder, means for turning said abutment axially to and fro from the main shaft and two longitudinal packing-strips in said abutment and separated a distance less than the length of the arc of the recess in the outer wall, in which the abutment rotates, substantially as herein shown and described.
5. In a rotary engine the combination with a cylinder and a rotary piston therein, of a re-

cessed cylindrical abutment, mounted to rotate axially parallel with the axis of the rotary piston in the cylinder and a recess in the outer cylinder-wall said abutment having a steam-duct the ends of which are in the periphery of the abutment, and which can register with steam-ducts in the cylinder-wall and an adjustable valve on the cylinder-wall for controlling the steam-ducts in the cylinder-wall and extending over an exhaust-port between said steam-ports, substantially as herein shown and described.

6. In a rotary engine the combination with a cylinder and a rotary piston therein, of a steam-chest on said cylinder, an adjustable valve in said chest, a duct extending from the steam-chest to an exhaust-channel in the cylinder-wall, a recessed cylindrical abutment mounted to rotate parallel with the piston-axis in a recess in the outer cylinder-wall and in the cylinder, said abutment having a steam-duct, the ends of which are in the periphery of the abutment, steam-ducts extending from the recess in which the abutment rotates to the steam-chest, such ducts as well as the exhaust-duct located between the steam-ducts being controlled by the valve in the steam-chest, substantially as herein shown and described.

7. In a rotary engine the combination with a cylinder and a rotary piston therein, of a steam-chest on said cylinder, an adjustable valve in said chest, a duct extending from the steam-chest to an exhaust-channel in the cylinder-wall, a recessed cylindrical abutment mounted to rotate parallel with the piston-axis in a recess in the outer cylinder-wall and in the cylinder, said abutment having a steam-duct, the ends of which are in the periphery of the abutment, steam-ducts extending from the recess in which the abutment rotates to the steam-chest and a duct extending from the steam-chest to the cylinder, such ducts as well as the exhaust-duct being controlled by the valve in the steam-chest, substantially as herein shown and described.

Signed at New York city, in the county of New York and State of New York, this 21st day of July, A. D. 1900.
